CLAIM

The ornamental design for a vehicle kitchen cabinet as shown and described.

DESCRIPTION

FIG. 1 is an overall view of a vehicle kitchen cabinet in a fully open status showing my new design;

FIG. 2 is another overall view of a vehicle kitchen cabinet thereof from the bottom;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is an enlarged view showing the portion 9 in FIG. 1;

FIG. 10 is an enlarged view showing the portion 10 in FIG. 2;

FIG. 11 is a schematic view showing a folded state;

FIG. 12 is a schematic view showing a second use state when the vehicle kitchen cabinet is fully opened; and,

FIG. 13 is a schematic view showing a third use state of a sliding of a cover plate.

The dot-dash lines depict the enlarged view boundaries that do not form part of the claimed design.
